ANIMATED DISPLAY RACK

Clarence L. Summers, Kansas City, Kans., assignor to Prism Plastics, Inc., Kansas City, Kans., a corporation of Kansas

Application December 8, 1947, Serial No. 143,033

Term of patent 3½ years

(Cl. D80—9)

To all whom it may concern:

Be it known that I, Clarence L. Summers, a citizen of the United States, residing at Kansas City, in the county of Johnson and State of Kansas, have invented a new, original, and ornamental Design for an Animated Display Rack, of which the following is a specification, reference being had to the accompanying drawing, forming a part thereof.

Fig. 1 is a front elevational view of an animated display rack, showing my new design.

Fig. 2 is a side elevational view thereof; and Fig. 3 is a plan view thereof.

I claim:

The ornamental design for an animated display rack, as shown.

CLARENCE L. SUMMERS.
